UNITED STATES PATENT OFFICE.

CHESTER R. PIEPER, OF LA CROSSE, WISCONSIN.

PULLEY MECHANISM.

1,233,601.

Specification of Letters Patent. Patented July 17, 1917.

Application filed January 11, 1915. Serial No. 1,677.

To all whom it may concern:

Be it known that I, CHESTER R. PIEPER, citizen of the United States, residing at La Crosse, in the county of La Crosse and State of Wisconsin, have invented a certain new and useful Improvement in Pulley Mechanism, of which the following is a full, clear, concise, and exact description, reference being had to the accompanying drawings, forming a part of this specification.

My invention relates to apparatus for supporting energy translating devices and includes the cord or string by which a translating device is supplied with energy which it is to translate, operating in conjunction with pulleys, and a supplemental supporting device whereby the vertical position of the translating device may readily be varied and adjusted.

The apparatus of my invention is of particular service in the support of incandescent lamps, current conducting cord being employed for furnishing the lamps with electric current and entering into the function of supporting the lamps.

My invention has as another of its characteristics the improved formation of a pulley housing or support having several novel and useful characteristics.

I will explain my invention more fully by reference to the accompanying drawing showing the preferred embodiment thereof and in which Figure 1 is a side elevation illustrating the preferred form of one adaptation of my invention; Fig. 2 is a view of one of the pulleys on line 2-2 of Fig. 1; Fig. 3 is a view on line 3-3 of Fig. 2; and Figs. 4 and 5 are detail views.

Like parts are indicated by similar characters of reference throughout the different figures.

The incandescent lamp 1 is of the drop light variety, the lamp being carried by and included in circuit by means of the usual pendant double cord 2 which is suitably anchored to the ceiling or other main support within a rosette 3, in accordance with common practice. The cord where adjacent the ceiling is returned upon itself to constitute a loop in the bight of which a floating pulley 4 is received, this pulley being suitably weighted to approximate the weight of the lamp and its shade whereby the pulley 4 will descend when the lamp 1 is elevated, and will hold the lamp when brought

to desired vertical adjustment. The loop, whose sides are thus changeable in length and whose bight is thus changeable in location in order that the lamp may be supported in its various positions of vertical adjustment, is maintained by means of a light or unweighted non-floating pulley 5 whose housing 6 is attached to the ceiling independently of the cord 2, rather than with the aid thereof as hitherto. The means by which the housing 6 of the pulley 5 is supported desirably includes a hook 7 secured to the ceiling or other uppermost and main support at the rosette 3. The hook 7 receives the eye 8 at the upper end of a link 9 whose lower end terminates in a hook 10 that receives the staple eye 11 upon the upper part of the housing 6.

By this arrangement the weight of the weighted pulley 4 is divided between the portion of the current conducting cord 2 attached to the ceiling and the link 9 instead of being borne altogether by this portion of the current conducting cord, as hitherto. Furthermore the weight of the lamp and its shade is not borne by this upper portion of the cord but is borne by the link 9 and the pulley 5 intervening between the link 9 and the lower stretch of the cord.

A rosette anchoring screw 12 also desirably passes through the stem of the hook 7 in order that this hook may be mounted in the desired place. The hook and link enable the upper pulley 5 to swivel so that it may be drawn in various directions and bodily turn to rotate on its axis without any undesirable side strain. When this pulley is released from any side thrusts or pulls it will readily return to its normal position. The elements 7, 8, 9, 10 and 11 thus constitute a flexible support for the upper pulley 5 whereby it may be mounted upon the ceiling or other main support in a manner to permit its position to be changed as desired.

The housings for the pulleys 4 and 5 desirably are of similar formation each being preferably of hollow globular shape, the lower and floating pulley housing 13 carrying iron slugs 14 in order that this pulley may be weighted, while the housing 6 for the upper and non-floating pulley is free of such slugs as this pulley serves to define the loop that holds the floating pulley 4 and therefore does not have to exert any counter-balancing effect to offset the weight of the

lamp and its shade. While the cord 2, herein shown, serves to convey energy in the form of electric current to a translating device in the form of an incandescent lamp, 5 I do not wish to be limited to the form of energy that the cord is adapted to convey nor to the nature of the translating device which the cord supports at its lower end.

I will now describe the improved formation of housing which is preferably employed in connection with each of the lower and upper pulleys 4 and 5. Each globular housing preferably includes two thin hemispherical metallic shells 15 which are united 15 at the top by the staple eye 11 and at the bottom by the staple 16. The hemispheric shells are provided with recesses 17, the recesses in each shell being symmetrical with respect to the recesses in the other 20 whereby passages are afforded to permit of the travel of the cord 2 through the globular housing. The long edges of the recesses 17 constitute seats for diaphragms 18 which are formed in a pair, the diaphragms being 25 united by a yoke 19 integrally formed therewith. The yoke is secured in relation to the hemispheric shells by the staple 11. The diaphragms are, in the main, surrounded by the shells but project beyond the same at the 30 recesses 17, the projecting portions of these diaphragms at the recesses 17 being bent over to constitute lips 20. A pulley shaft 21 projects through flanged holes in the diaphragms for the support of the housed pulley, the portion of the shaft intermediate the diaphragms being larger than these 35 holes to have end engagement with the diaphragms and being of such length as to constitute a distance preserver to maintain 40 the diaphragms snugly upon their seats at the recesses 17. The shaft 21 is dropped sufficiently to afford ample clearance between the groove of the pulley and the upper

portion of the housing for the passage of the cord.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A pulley structure including a pulley; 55 and a housing therefor formed of two shells, a diaphragm seated upon each of the shells upon and between which diaphragms the pulley is mounted, the pulley having a distance preserving portion intervening between the diaphragms to maintain the diaphragms in engagement with the shells.

2. A pulley structure including a pulley; and a housing therefor formed of two shells, 65 a diaphragm seated upon each of the shells upon and between which diaphragms the pulley is mounted, the pulley having a distance preserving shaft portion intervening between the diaphragms to maintain the diaphragms in engagement with the shells. 70

3. A pulley structure including a pulley; a housing therefor formed of two shells, a diaphragm seated upon each of the shells upon and between which diaphragms the pulley is mounted; and a distance preserving 75 portion intervening between the diaphragms to maintain the diaphragms in engagement with the shells.

In witness whereof, I hereunto subscribe my name this fourth day of December A. D. 80 1914.

CHESTER R. PIEPER.
